Inventor

Joseph E. Wood.

UNITED STATES PATENT OFFICE.

JOSEPH E. WOOD, OF SEATTLE, WASHINGTON, ASSIGNOR TO ELECTRICAL ADVERTISING COMPANY, LIMITED, OF VANCOUVER, BRITISH COLUMBIA, CANADA, A CORPORATION OF BRITISH COLUMBIA.

DISPLAY APPARATUS.

1,084,121.

Specification of Letters Patent.

Patented Jan. 13, 1914.

Application filed May 2, 1910. Serial No. 559,010.

To all whom it may concern:

Be it known that I, JOSEPH E. Wood, a citizen of the Dominion of Canada, and a resident of the city of Seattle, in the county 5 of King and State of Washington, have invented certain new and useful Improvements in Display Apparatus, of which the following is a specification.

My invention has for its primary object 10 the provision of a novel apparatus of the above type, wherein a variety of subjects can be intermittently displayed automatically.

A further object resides in the provision 15 of an apparatus by which the actuator is automatically connected and disconnected for successively moving a plurality of display cards.

Further my invention aims to provide 20 means whereby the actuator and the associated catch device can be reversed in their operation to effect a return movement of the display cards.

With the above and other objects in view, 25 to be referred to as my description progresses, my invention resides in the features of construction, and combinations of parts hereinafter described and succinctly defined in my annexed claims.

30 Referring to the accompanying drawings, illustrating my invention in such form as now preferred by me: Figure 1 is a longitudinal section of my display apparatus, taken on line 1—1 of Fig. 2. Fig. 2 is a section taken on line 2—2 of Fig. 1 with the display cards removed. Fig. 3 is a fragmentary detail view of the reversible drive mechanism. Fig. 4 is a fragmentary section of the support, and illustrating the cam and 35 its stop mechanism therein, in its two positions of adjustment. Fig. 5 is a plan illustrating more particularly the actuator, and the catch device and controlling cam thereof. Fig. 6 is an edge view of the cam. Fig. 7 is a fragmentary vertical section on large scale, 40 and Fig. 8 is a detail of one of the hinges. Fig. 9 is a detail of one of the hinges.

In carrying out my invention I provide a plurality of what I term "display cards," the same being of any suitable construction 45 as to be capable of bearing the desired matter to be displayed, and supported for movement, whereby they can be adjusted and thereby be successively exposed.

In my present construction I provide car-

riers 1, having upper and lower substantially U-shaped holders or seats 2 in which the display cards 3 are preferably removably engaged, said carriers being connected for traveling in arcuate paths, by hinges 5, engaged with common pivots 6 of a support 4. 55 These carriers 1 are also preferably engaged with curved guides 6' of the opposite heads 4' of said support, the same being conveniently cut out in their upper and lower edge portions to engage over the said guides 65 6', as clearly shown in Fig. 1.

Reference numeral 7 indicates the actuator and 8 a catch device, the latter having a follower 8' engaged with a cam 9, which cam controls the operation thereof to swing the 70 carriers 1 successively. Catch device 8 is slidably supported in a guide way 7' of actuator 7 for projection to and from the path of movement of the carriers 1, which carriers are conveniently provided with 75 engaging parts, in the form of strike lugs, as 1', arranged in spaced relation, whereby they will be successively engaged by said catch device. Actuator 7 is supported for rotary and axial adjustments, the same, as 80 now considered, being fixed to a screw shaft 9a engaged with a nut part 10 of support 4.

Reference numeral 11 indicates a driven shaft rotatably supported in one head 4' and telescopically engaged with shaft 9a, 85 and 12 indicates a key projecting through shaft 11 into a key way 9' of shaft 9a, thereby connecting said shafts for simultaneous movement while permitting of independent lengthwise adjustment of shaft 9a. Cam 9 90 is confined between actuator 7 and a fixed collar 13, of shaft 9a, in engagement therewith, so that when not held by a stop device 14 to be described, it is held by friction between said parts so as to rotate with the 95 shaft. This stop device 14 is loosely fitted on a depending hub part of cam 9, as shown, and has a finger which projects outwardly between lugs 15 of the cam, to engage one or the other of stop lugs 1'' of support 1, this 100 depending on the direction of rotation of shaft 9a, and thereby hold the cam against movement in one direction. Said cam, is however, obviously free to move in the reverse direction and therefore, when the direction of rotation of shaft 9a is reversed, by mechanism to be later described, said cam through its frictional engagement with

actuator 7, collar 13 and follower 8' is rotated until stop device 14 engages the other stop lug 1''. Such an adjustment of cam 9, as indicated by broken lines in Fig. 4, obviously reverses the action of catch device 8, compelling the same to connect and release the carriers to swing the latter in the reverse direction or back to their first position.

Reference numeral 16 indicates a drive shaft which may be connected with a motor in any suitable manner, the same being provided with a beveled friction wheel 17 with which similar friction wheels 18, 18' forming a part of a reversible driving mechanism, are associated, said friction wheels 18, 18' being carried by a slideable sleeve 19, whereby they can be alternately shifted into engagement with wheel 17. Sleeve 19 is connected, by a spline 19', with a shaft 20 for simultaneous rotary and relative lengthwise movement, such connection enabling power being transmitted through the worm and worm wheel gearing 21 to shaft 11, while permitting of wheels 18, 18' being thrown into and out of operative engagement, as hereinbefore set forth.

Reference numeral 22 indicates a shifter arm connected with shaft 9^a between collars 22' thereof, and provided on its free or lower end portion with spaced shoulders or lugs 23 between which one arm of a bell crank lever 24 projects to be alternately engaged thereby. Lever 24, which is pivoted, as at 24', has the other of its arms engaged between shoulders 25 of sleeve 19. A spring 26 secured to said last named arm of bell crank 24 and to a relatively fixed part on the opposite side of its point of swing, serves to swing the bell crank after its said arm 40 has been advanced by shifter 22 slightly to either side of its central position.

In operation, shaft 9^a is rotated carrying with it actuator 7 and catch device 8, which latter is projected and retracted by cam 9 to effect the connection and release between the actuator and carriers 1. During this rotary movement, through the screw threaded engagement with nut part 10, said shaft 9^a is also adjusted to shift actuator 7 and its catch device, whereby the latter is presented to engage strike lugs 1' successively. After all of the carriers have been thus moved, gear 18' is shifted into engagement with drive gear 17 through the medium of shifter 22, bell crank 24 and spring 26. This effects a reversal in the operation of shaft 9^a, with a consequent resetting of cam 9, as to the dotted position in Fig. 4, as hereinbefore described.

Having thus described my invention, what I claim as new and desire to secure by Letters Patent of the United States of America, is:

1. A display apparatus comprising a plurality of carriers supported for movement,

an actuator therefor supported for axial and rotary movements, a catch device supported on said actuator for relative movement to connect said carriers therewith, means for rotating said actuator and simultaneously moving the same axially, engaging parts on said carriers arranged to be successively engaged by said catch device during axial movement of said actuator, and means for operating said catch device alternately to engaging and releasing positions, during movement of said actuator.

2. A display apparatus comprising a plurality of carriers swingingly supported, a rotatable actuator for swinging said carriers, means for rotating said actuator in opposite directions, a catch device supported on said actuator for relative movement outwardly from its axis to connect said carriers therewith, and means for operating said catch device by and during movement of said actuator in both directions of its movement.

3. A display apparatus comprising a plurality of carriers supported for movement, an actuator for moving said carriers, means for operating said actuator in relatively opposite directions, a catch device for connecting said carriers for movement by said actuator, and means controlling the operation of said catch device set to effect relatively reverse operations thereof during reverse movements of said actuator.

4. A display apparatus comprising a plurality of swingingly supported carriers, an actuator for swinging said carriers, means for operating said actuator to effect swinging of said carriers in reverse directions, a catch device for successively connecting said carriers with said actuator, and means controlling the operation of said catch device to connect and disconnect said carriers at predetermined points in the path of said actuator, said last means being set for relatively reverse operations of said catch device by and during reverse movements of said actuator.

5. A display apparatus comprising a plurality of swingingly supported carriers, a rotatable actuator for swinging said carriers, means for rotating said actuator in reverse directions, a catch device operated by and during movement of said actuator for connecting said carriers successively, and means controlling said catch device to reverse the same in its operation to effect swinging of said carrier in reverse directions.

6. A display apparatus comprising a plurality of swingingly supported carriers, a rotatable actuator for swinging said carriers, means for rotating said actuator in reverse directions, a catch device operated by and during movement of said actuator for connecting said carriers successively, and means operated by and during reverse movements of said actuator, rotating means controlling

said catch device to reverse the same in its operation, whereby said carriers are swung in reverse directions.

7. A display apparatus comprising a plurality of swingingly supported carriers, a rotatably supported actuator, means for rotating said actuator in opposite directions, a catch device supported on said actuator for projection into the path of said carriers, a rotatably supported cam engaged with said catch device for effecting the projection thereof during rotation of said actuator in both directions, and means normally holding said cam against movement relatively to said actuator.

8. A display apparatus comprising a plurality of swingingly supported carriers, a rotatably supported actuator, means for rotating said actuator in opposite directions, a catch device supported on said actuator for projection into the path of said carriers, and a cam for effecting the projection of said catch device moved automatically during reverse movements of said actuator for vary-

ing the point of projection of said catch device.

9. In a leaf-turner, the combination with a series of hinged leaf-holders, of a traveling actuator constructed and arranged to turn said leaf-holders successively, means for giving said actuator a continuous spiral movement first in one direction and then in the other direction, and means for giving said actuator an intermittent radial movement to release the holders.

10. In a leaf-turner, the combination with a series of hinged leaves, of a leaf actuator having a spiral movement, means for giving the actuator said spiral movement, and means for automatically reversing the direction of travel of said actuator, said means controlled by said actuator.

Signed at Seattle, Washington this 24th day of April 1910.

JOSEPH E. WOOD.
